UNITED STATES PATENT OFFICE.

STEPHEN E. JACKMAN, OF NEW YORK, N. Y.

CAR-COUPLING.

SPECIFICATION forming part of Letters Patent No. 743,169, dated November 3, 1903.

Original application filed September 27, 1902, Serial No. 125,092. Divided and this application filed August 20, 1903. Serial No. 170,169. (No model.)

To all whom it may concern:

Be it known that I, STEPHEN E. JACKMAN, a citizen of the United States, and a resident of the city of New York, Coney Island, borough of Brooklyn, in the county of Kings and State of New York, have invented a new and Improved Car-Coupler, of which the following is a full, clear, and exact description, this being a division of the application for Letters

10 Patent of the United States, Serial No. 125,092, filed by me September 27, 1902.

The invention relates to amusement devices, such as inclined or switch-back railways; and its object is to provide a new and 15 improved car-coupler for convenient and safe coupling of the cars and arranged to prevent coupled cars from jumping upward off the track, especially when running over steep inclined portions in the track of the railway.

20 The invention consists of novel features and parts and combinations of the same, as will be more fully described hereinafter and then pointed out in the claims.

25 A practical embodiment of the invention is represented in the accompanying drawings, forming a part of this specification, in which similar characters of reference indicate corresponding parts in all the views.

30 Figure 1 is a side elevation of the improvement, showing two cars coupled together. Fig. 2 is a plan view of the same. Fig. 3 is an enlarged side of the improvement as applied and showing the car-axles in sections; and Fig. 4 is a like view of the same, showing 35 the parts in a different position.

35 Each of the cars B B is provided with a longitudinally-extending draw-bar O, fulcrumed at O' in the truck-frame and extending over a guide-plate B' beyond the end of the car, as 40 shown in the drawings. The outward end of the draw-bar is connected by a transverse pivot O² with a coupling-link O³, having a lug or projection O⁴ at each end, adapted to swing in engagement with the top of the draw-bar 45 O to prevent the coupled cars from jumping upward off the track-rails. On the end of each car and directly over the draw-bar O is arranged a bracket O⁵ to prevent the projecting end of a draw-bar from being bent upward 50 on an unusual strain.

By reference to Fig. 1 it will be seen that the bottom edges of the lugs O⁴ stand normally at angles to the top surfaces of the draw-bars O to allow the adjacent coupled cars to readily travel over portions of the 55 track curved in a vertical plane; but in case a rear car should unduly press a forward car, then the draw-bar of the rear car causes an upward swinging of the connecting-link on the other draw-bar as a fulcrum until the lug 60 abuts against the draw-bar of the forward car, thus holding this car down and preventing further upward swinging of the connecting-link, so that the following car cannot leave the track. (See Fig. 4.)

65 By having the draw-bars mounted to swing on vertically-disposed pivots, as shown, the cars are free to readily travel around sharp curves disposed in a horizontal plane without undue binding of the coupling members.

70 Having thus described my invention, I claim as new and desire to secure by Letters Patent—

1. A car-coupling comprising a longitudinal draw-bar pivoted on the car, to allow the 75 draw-bar to swing sidewise, a coupling-link pivoted on the draw-bar and arranged to swing up and down, and a lug on the coupling-link, adapted to engage the top of the draw-bar, to prevent the car from swinging 80 up, as set forth.

2. A car-coupling comprising a longitudinal draw-bar pivoted on the car, to allow the draw-bar to swing sidewise, a coupling-link provided on the draw-bar and arranged to 85 swing up and down, a lug on the coupling-link, adapted to engage the top of the draw-bar, to prevent the car from swinging up, and a fixed stop on the car, over that portion of the draw-bar projecting beyond the car, as 90 set forth.

3. A car-coupler comprising longitudinal draw-bars pivoted on the cars and mounted to swing in a horizontal plane, and a coupling-link pivotally connecting the free ends 95 of the draw-bars with each other, the coupling-link being capable of swinging in a vertical direction, as set forth.

4. A car-coupler comprising longitudinal draw-bars pivoted on the cars and adapted 100

to swing in a horizontal plane, a coupling-link pivotally connecting the free ends of the draw-bars with each other, the coupling-link being capable of swinging in a vertical direction, and lugs on the ends of the coupling-link, for engagement with the draw-bars, as set forth.

In testimony whereof I have signed my name to this specification in the presence of two subscribing witnesses.

STEPHEN E. JACKMAN.
